UNITED STATES PATENT OFFICE.

CLARENCE W. CROSS, OF GRINNELL, IOWA.

DESIGN FOR A CLOTHES-POUNDER.

SPECIFICATION forming part of Design No. 27,353, dated July 13, 1897.

Application filed January 25, 1897. Serial No. 620,690. Term of patent 14 years.

To all whom it may concern:

Be it known that I, CLARENCE W. CROSS, a citizen of the United States of America, residing at Grinnell, in the county of Poweshiek and State of Iowa, have invented and produced a new and original ornamental Design for a Clothes-Pounder, of which the following is a specification, reference being had to the accompanying drawings, in which—
Figure 1 is a perspective view showing the exterior configuration thereof, and Fig. 2 is a vertical sectional view showing the interior.
The letter A designates the base of the design in the form of a truncated cone, made of tin-plate or other suitable sheet metal.

A cluster of sheet-metal cones B is fixed in the top portion of the base A by soldering or in any suitable way and united at their top ends and then jointly fixed in the lower end

of an open-ended tube C in such a manner 20 that the exterior of each one in the cluster will be visible.

H represents a small cone fixed at the top end to the tube C by soldering or in any suitable way, so that it covers the top end portion 25 of the cluster of cones and the lower portion of the tube C.

All the parts are rigidly united to thus produce an ornamental clothes-pounder in which the cluster of cones is a conspicuous part. 30

What I claim is—

The design for an ornamental clothes-pounder, substantially as shown and described.

CLARENCE W. CROSS.
